UNITED STATES PATENT OFFICE.

EDWARD C. STEARNS, OF SYRACUSE, NEW YORK.

DESIGN FOR A PULLEY-FRAME.

SPECIFICATION forming part of Design No. 18,536, dated August 14, 1888.

Application filed June 9, 1888. Serial No. 276,640. Term of patent 14 years.

To all whom it may concern:

Be it known that I, EDWARD C. STEARNS, of Syracuse, in the county of Onondaga, in the State of New York, have invented new and useful Improvements in Designs for Pulley-Frames, of which the following, taken in connection with the accompanying drawings, is a full, clear, and exact description.

This invention relates to a novel design for pulley-frames; and it consists in the peculiar conformation of the same, substantially as shown in the accompanying drawings, in which—

Figure 1 is a side view, and Fig. 2 an edge view, of my design.

The leading feature of my design consists in the contour of the frame, which is formed with the downwardly - extending edges *a*, which unite by a sharp corner with the inward curves *a'*, extending down to and encircling the hub. Down the center of each side of the frame extends a flange, *b*, curved outward and then slightly inward, as shown. The pulley-frame

is provided with a ring in its upper end, of the usual form, and is also provided with a pulley-wheel, *C*.

The outlines of my design, as described and shown, blend together and form an article that is attractive by its light and graceful appearance, and is therefore more salable.

Having thus fully described my design, what I claim is—

The design for pulley-frames herein shown and described, the same consisting, essentially, of a frame formed with the inclines *a*, the curves *a'*, joining around the hub, and the projecting flanges *b*, having curved edges.

In testimony whereof I have hereunto signed my name, in the presence of two attesting witnesses, at Syracuse, in the county of Onondaga, in the State of New York, this 14th day of March, 1888.

EDWARD C. STEARNS.
